ABSTRACT

A universal method of rolling rails and a mill train for the same comprises an edging rolling mill set anterior to or/and posterior to a universal rolling mill. The edging rolling mill consists of a first rail edging roll pass and a second edging roll pass containing a set of the pass designs so different as to have the radii to meet respective corners of the head and of the foot of the so-rolled rail made larger than those of the pass designs of the first edging roll pass. The second edging roll pass is operated in combination with the universal rolling mill so as to conduct rolling following the rolling operation of the universal rolling mill and the first edging roll pass.

UNIVERSAL METHOD OF ROLLING RAILS AND A MILL TRAIN FOR THE SAME

BACKGROUND OF THE INVENTION

1. Field of the Invention

The present invention relates in general to a method of rolling rails and the mill train for the same, and more particularly to a method of rolling rails by a special edging rolling mill in combination with a universal rolling mill and a mill train for the same.

2. Description of the Prior Art

Generally, rolling of rails is done by the so-called "rolling method of roll pass type," wherein rolling is carried out with upper and lower horizontal rolls having pass designs. However, this rolling method requires a high level of operation technique; the pass designs used for the method are difficult to design and manage; and products rolled by this method are not precise as to shape. Therefore, with the low rate of passing the specifications of products of high precision, and because of low productivity of the method, products are inevitably high-priced.

In order to solve such problems as mentioned above, the universal rolling mill method is gaining popularity. The universal rolling method is fundamentally different from the above rolling method of the roll pass type. The former uses a universal rolling mill with the horizontal rolls and vertical rolls concentrating reduction on every part of the to-be-called material, particularly the upper surface and both sides of the part to be rolled into the head of the rail which will contact wheels, thus producing a rail having a head of good quality resulted from sufficient forging.

However, this method is so carried out that the material to be rolled into a rail is several times reciprocally subjected to the universal rolling mill and edging rolling mill. However, particularly in the case of rolling such products as rails that have the head and the foot reduced greatly differently, even the rolling operation by this method is impossible, for the following reason. When rolling the material to be rolled into a rail by using the universal rolling mill, part of the reduction power put on the head and the foot of the rail works so as to make them stretch in their respective directions, and moreover they are subjected to the reduction of the same rate, making the reduction of the head greater than that of the foot. This causes a great difference in the above stretched volume between the head and the foot. Even with respect to the head of the rail, the stretched volume varies top to bottom. Subsequent to the universal rolling mill, the rail is sent to the edging rolling mill which is equipped with the roll pass so designed as to put the same reduction rate to the head and the foot, but the passing of such to-be-rolled material as the rail having the head and the foot with greatly different stretched volumes causes different reduction rates between these parts, thus causing such troubles as bending of the so-called products, these troubles making any further reciprocal rolling impossible. Even if such rolling can be carried out, the corners of the head and of the foot of the so-rolled rail will form an acute angle, which constitutes a fatal shortcoming of the prior art method. Thus, it is believed to be difficult to develop an effective and economical universal rail rolling method.

SUMMARY OF THE INVENTION

An object of the present invention is to provide a universal method of rolling rails, whereby the reciprocal rolling of rails is made possible by using an edging roll mill which can shift swiftly to a second edging rod for rolling the corners of the head and of the foot of the so-called rail so as to not form an acute angle. These corners are all formed by using, in addition to the normal pass design, a second pass design with radii to cause the corners to be made larger than those of the above-mentioned normal pass design, whereby a rail having a sufficiently forged head can be produced, thus solving the above-mentioned problem of the universal rail rolling method which has been in use.

Another object of the present invention is to provide a mill train for rolling rails of high accuracy in size and shape, which requires no rolls of the roll pass type and which can be operated very easily compared with the operation of the rolling method of the roll pass type.

In order to attain these objects, the present invention is developed in relation to a method of rolling rails by using a rolling mill train comprising a universal rolling mill, an edging rolling mill, a finishing rolling mill, etc., wherein said edging rolling mill is set anterior to and/or posterior to said universal rolling mill, and said edging rolling mill consists of a first rail edging roll pass (hereafter called the "first edging roll pass") and a second roll pass (hereafter called the "second edging roll pass") containing a set of the pass designs so different as to have radii to form respective corners of the head and the foot of the so-rolled rail larger than those of the pass designs of the first edging roll pass. The rolling operation is carried out by using the combination of the second edging roll pass with the universal rolling mill following the rolling operation using the universal rolling mill and the first edging roll pass.

BRIEF DESCRIPTION OF THE DRAWINGS

FIG. 1 shows a plan sketch of the universal rail rolling mill train conventionally in use.

FIG. 2 shows a plan perspective, with partial sections rotated, of the rolling operation as it is carried out by the universal rolling mill *u*, the edging rolling mill *E* and the finishing rolling mill *F* shown in FIG. 1.

FIG. 3 shows the progress of the material as it is rolled by the universal rolling mill shown in FIG. 2.

FIG. 4 shows the progress of the material as it is rolled by the edging rolling mill shown in FIG. 2.

FIGS. 5A-C show universal rail rolling mill trains according to the present invention.

FIG. 6 shows the progress of the material as it is rolled according to the present invention.

DESCRIPTION OF THE PREFERRED EMBODIMENT

The following is an explanation of the present invention in comparison with the conventional rolling method which has such problems as mentioned above.

FIGS. 1 and 2 show the conventional type of the universal mill train for rolling rails, in which a rough-rolled billet having a symmetrical section which has passed through the blooming rolling mill *V1* and the breakdown rolling mill *V2*, is several times reciprocally subjected to the universal rolling mill *u* and the edging rolling mill *E*. As is known, the universal rolling mill *u* has the horizontal rolls 6 and 7 to roll the web of the so-rolled rail from above and below and the vertical rolling mills 4 and 5 to roll the head 1 and the foot 2 of the so-rolled rail from both sides (since FIG. 2 is a plan diagram with sections of the rolls and rails rotated, the horizontal rolls appear vertical, and vice versa); and the edging rolling mill *E* has the upper and lower horizontal rolls 8 and 9 with pass designs to edge the material which has passed through the universal rolling mill *u*. After having passed through the edging rolling mill *E*, the material is sent to the final finishing rolling mill which is indicated with the sign *F*. In FIG. 1, the line with the arrows shows the passage of the to-be-rolled material; 10 indicates the motor of each mill.

Using FIGS. 3 and 4, the rolling of the material during the reciprocated subjection to the universal rolling mill *u* and the edging rolling mill *E* after having passed through the breakdown rolling mill *V2*, is explained, as follows:

Having passed through the breakdown rolling mill *V2*, the material is sent to the universal rolling mill *u*. In this mill, the positions, at the first pass, of the vertical rolls 4 and 5 and the upper and lower horizontal rolls 6 and 7 are indicated respectively with 4-1, 5-1, 6-1 and 7-1, as they are reducing respectively the head 1, and foot 2 and the web 3. Then, the material is sent to the edging rolling mill *E*, as shown in FIG. 4; and the positions, at the first pass, of the horizontal rolls 8 and 9 are indicated respectively with 8-1 and 9-1.

The material continues to be reciprocally subjected, as prescribed, to the universal rolling mill u and the edging rolling mill E ; and, at the third pass, respective rolls of the universal rolling mill u are positioned at 4-3, 5-3, 6-3 and 7-3, and the horizontal rolls 8 and 9 of the edger rolling mill E are positioned respectively at 8-3 and 9-3. In the figure, rolling actions are shown in three passes. In actual cases, however, they are sometimes carried out five to seven or more passes.

In this case, the upper and lower horizontal rolls and the vertical rolls of the universal rolling mill u are so designed as to form any desired cross-section. Therefore, no acute angle is produced on the corners of the head 1 and the foot 2. However, the horizontal rolls 8 and 9 of the edging rolling mill E have pass designs, so they are adjustable only in the upward and downward direction. This causes certain parts of the head 1 and the foot 2 not to meet the pass designs as rolling operation progresses. That is because, after the fifth pass of the head 1 of the so-rolled rail, there is produced a difference of ΔH in reduction from the first pass, causing the head 1 of the so-rolled rail, at least its corner A, to leave and be free from contact by the pass designs of the horizontal rolls of the edge rolling mill.

After being finished, corner A should have the prescribed radius R_1 . But, since it has not been contacted by the pass designs of the edge rolling mill, the corner tends to have a shape of an acute angle; and residual stress is produced there due to insufficient forging. The head 1 of the so-rolled rail is subjected to concentrated reduction by train wheels, and therefore it should be subjected to sufficient forging by the rolling mill prior to such concentrated reduction, and should have such a profile as to stand actual severe use. For this purpose, there has been known the availability of the tandem rolling mill train having a number of universal rolling mills and edging rolling mills arranged alternately. But this sort of the rolling mill train is too expensive to be commercially practicable.

Also on the corner B of the foot 2 there will be seen the same situation. That is to say, even if the pass design is so constructed as to produce the prescribed curve rate on said corner B, as the rolling operation progresses, say, at the third pass, the difference of Δ occurs, causing the corner to not be contracted by the pass design. Said corner B of the foot 2 of the so-rolled rail should have its radius designed so as not to damage rail sleepers or gather rust. Once an undesirable profile is formed at that stage, it is impossible to correct it by the finishing rolling mill F .

In order to solve such problems as mentioned above taking place in rolling rails by reciprocal subjection to the universal rolling mill and the edging rolling mill, the present invention provides, in addition to the abovementioned edging roll pass, a second edging roll pass in the edging rolling mill E . This causes, at the latter stage of rolling operation, the prescribed radiiuses for respective corners of the head and the foot of the so-rolled rail to be formed by the other edging roll pass.

As mentioned above, the present invention is characterized by the arrangement of a blooming rolling mill, a universal rolling mill, an edging rolling mill, a finishing rolling mill, etc., and the rolling method using such arrangement of the rolling mills, wherein the edging rolling mill set near anterior and/or posterior to the universal rolling mill is provided with a second edging roll having such pass design as to form the curve rates prescribed to meet the corners of the head and the foot of the so-rolled rail, and the second edging roll is so designed as to move in a direction perpendicular to the rolling line.

The following is to explain the present invention concretely using the preferred examples shown in the drawings:

In FIG. 5, V_1 , V_2 and u indicate respectively a blooming rolling mill, a breakdown rolling mill and a universal roughing rolling mill; E_1 and E_2 indicate respectively a first edging roll and a second edging roll, of which pass designs are different one from the other; and F indicates a universal finishing rolling mill. In the rolling mill train shown in FIG. 5A, a steel

billet is bloomed and roughed respectively by the blooming rolling mill V_1 and the roughing rolling mill V_2 , and then subjected reciprocally in several passes to the edging roll E_1 , and the universal roughing rolling mill u . In the latter stage of

5 rolling operation, are employed the universal rolling mill u and the second edging roll E_2 , which replaces the edging roll E_1 on the rolling line by moving the edging rolls E_1 and E_2 in the direction indicated by the arrow. FIG. 5B shows a rolling mill train, in which the first edging roll E_1 and the second edging roll E_2 having different pass designs one from the other, are arranged posterior to the universal roughing rolling mill u . FIG. 5C shows a rolling mill train, in which the first edging roll E_1 and the second edging roll E_2 and another set of such rolls E'_1 and E'_2 having different pass designs one from the other are arranged respectively anterior and posterior to the universal roughing rolling mill u .

The rolling method by using the rolling mill trains shown in FIG. 5B and 5C, is the same as that by using the rolling mill train shown in FIG. 5A. But when using the rolling mill train shown in FIG. 5C, there are seen such advantages that while either of the edging rolls in used, the other acts as a guide, and while either of them is replaced after being worn out by a long period of use, the other can carry out rolling smoothly and perfectly. FIG. 6 shows the enlarged view of the rolling operation carried out in the abovementioned situation. In the figure, the to-be-rolled material has been reduced by two passes through the universal rolling mill u and the edging roll E_1 so as to have a certain cross-section, which process is the same as 20 that used in the conventional method. In this case, as mentioned above, the corner A of the head 1 and the corner B of the foot 2 of the so rolled rail form an acute angle to some extent.

In the latter stage of rolling operation after the above mentioned, said edging roll E_1 is made to move out of the rolling line, and instead of this roll, the second edging roll E_2 is set on the rolling line, by movement of the edging rolling mill E itself or otherwise.

In comparison with the pass design of the edging roll E_1 , 40 that of the edging roll E_2 is smaller in the height of the part corresponding to the head 1 of the so-rolled rail and also in the thickness of the part corresponding to the foot 2; and also the second edging roll E_2 has pass designs with the radius R_1 for the corner A of the head 1 of the so-rolled rail and with the radius R_2 for the corner B of the foot 2. The material to be rolled into a roll is made to pass, one or two times, through the universal rolling mill u and the second edging roll E_2 . Thus, by these passes, the corner of the head and the corner of the foot of the so-rolled rail will be formed into the desirable profile having the prescribed radii R_1 and R_2 . The so-rolled rail is then subjected to the final finishing rolling mill F to become a final product. The radius R_1 of the corner A of the head must be made larger than the radius formed by the edging roll E_1 of the former edging rolling mill. This is particularly to forging the corner of the rail which will be subjected most severely to mechanical impact.

As will be apparent from FIG. 6, in the universal mill u , the portions of the rail material other than the side surfaces (indicated by dotted lines in FIG. 6) of the head 1 and the foot 2 are subjected to rolling reduction by the vertical rolls 4 and 5 and by the upper and lower horizontal rolls 6 and 7. By this reduction, (pass 6-1 in FIG. 6) The side surfaces of the head 1 and the foot 2 swell out to some extent.

65 The rail material rolled by the aforesaid universal mill is then reduced by the first pair of rolls E_1 of the edging mill E . The edging rolls E_1 reduce the material excluding the top surfaces of the head 1 and the bottom surface of the foot 2 (respectively indicated by dotted lines in FIG. 6,) thus reducing the sides of the head 1 and foot 2 which have not been subjected to reduction by the previous passage through the universal mill u (pass E-1 1 in FIG. 6).

By performing several passes through the universal mill u and the edging mill E employing the edging rolls E_1 while narrowing the interval between the respective opposed rolls, both

rolls *u* and *E* cooperate in complementary reduction of the material into an intended rail configuration. Subsequent passes through *u* and *E*1 are represented by 6-2 and *E*1-2 in FIG. 6.

Following the above described rolling, the universal mill *u* and the second pair of edging rolls *E*2 of the edging mill *E* are used for subsequent rolling. In FIG. 6 these passes are represented by 6-3 and *E*2-1, respectively. In this subsequent rolling, the edging mill *E* with rolls *E*2 mainly reduces the sides of the head 1 and the foot 2 which respectively include the corners A and B shown in FIG. 4. The portions of rolls *E*2 which contact corners A and B are so formed that the radius of curvature *R*1 on the border between the top surface of the head 1 and each of the side surfaces thereof and the radius of curvature *R*2 on the border between the bottom surface of the foot 2 and each of the side surfaces thereof are larger than the respective radii of rolls *E*1. Therefore, the corners A and B of the rail can be reduced sufficiently to be rounded and forged to a substantially increased degree.

As mentioned above, by employing the rolling mill train and the rolling method according to the present invention, it is possible to produce rails of high accuracy in size with a single universal rolling mill and an edging mill which are inexpensive. The quality of the so-rolled rail is as good as or even better than that of rails which are produced by such well-known, but expensive rolling equipment as the tandem rolling mill.

We claim:

1. In the method of rolling rails by employing a universal rolling mill and an edging rolling mill, the improvement of the universal rail rolling method which comprises:

rolling a roughly rolled billet into a rail by reciprocation thereof through said universal rolling mill and a first pair of edging rolls of said edging rolling mill, the progress of the reciprocative rolling causing the corners of each of the head and foot of the rail to become unaffected by the roll pass of said edging rolling mill, subsequently replacing said first pair of edging rolls of said edging rolling mill by a second pair of edging rolls by shifting the latter rolls to the rolling line, said second pair

of edging rolls having a contour such that the portions thereof which meet the corners of each of the head and foot of said rail have larger radii than those of the corresponding portions of said first pair of edging rolls, and again rolling the material subjected to the aforesaid reciprocative rolling, by the reciprocative passage through said second pair of edging rolls and said universal rolling mill, and finally rolling the thus rolled material into a finished rail by a finishing rolling mill.

2. In a universal rail rolling mill train including a universal rolling mill and an edging rolling mill, a rail being formed by reciprocating a roughly rolled billet back and forth through said universal rolling mill and said edging rolling mill; the improvement wherein said edging rolling mill comprises a first pair of edging rolls and a second pair of edging rolls, said pairs of edging rolls having portions formed to contact the corners of the head and foot of said roughly rolled billet while being formed into said rail, said portions of said second pairs of edging rolls have larger radii than said portions of said first pair of edging rolls; and means mounting said pairs of edging rolls for selectively shifting one of said pairs into the path of rolling of said rail and the other of said pairs out of said path.

3. The improvement claimed in claim 2, wherein said edging rolling mill is positioned anterior to said universal rolling mill.

4. The improvement claimed in claim 2, wherein said edging rolling mill is positioned posterior to said universal rolling mill.

5. The improvement claimed in claim 2, wherein said edging rolling mill is positioned anterior to said universal rolling mill, and further comprising a second edging rolling mill identical to the first edging rolling mill positioned posterior to said universal rolling mill.

6. The improvement claimed in claim 2, wherein said mounting means slides said pairs of edging rolls in a direction perpendicular to said path.

7. The improvement claimed in claim 2, wherein said second pair of edging rolls is dimensioned such that the part thereof contacting the head of the rail is shorter and the part thereof contacting the foot of said rail is thinner than the corresponding parts of said first pair of edging rolls.
